UNITED STATES PATENT OFFICE

2,425,826

HEAT EXCHANGER

William Radtke, Chicago, Ill., assignor to Mojon-
nier Bros. Co., a corporation of Illinois

Application January 29, 1945, Serial No. 574,989

2 Claims. (Cl. 257—187)

1

The present invention relates to heat exchangers of the trickle type wherein the heat exchange units are pivoted or hinged to swing about parallel axes and has to do more particularly with the mounting of the same.

One object of the invention is to arrange the parts so that the several leaves or units may be individually assembled and removed for repair or otherwise with a minimum of effort. This is brought about by having most of the projecting pivots enter the headers from the top. There are at least four headers and four pivots for each unit of the heat exchanger wherein the invention is used. One of the headers and its pivotal connection are reversely positioned in order to provide for an opposition of forces within the exchanger. It has also a separable coupling or union which enables it to be moved out of the way when assembling or disassembling the unit.

Another object is to so construct the headers and their pivots that the use of gaskets is avoided. The only place where a gasket is used is in the sanitary coupling or union which is employed with reversed connection.

Another object is to set the tubular pivots in the holes of the headers in such a way as to insure a perfectly horizontal positioning of the distributor on the top edges of the several leaves or units when in operative position. In other words, the top edges of the leaves must lie in a perfectly horizontal plane. To bring this about, I employ a novel construction of stuffing box. In the four-header construction, two of the headers, one a reversely positioned header, have ledges or bearing steps at the bottoms of the pivot receiving holes that take up the thrust of the pivots, due to their reversed positions, and there, by being carefully made, serve to maintain the proper setting of the distributor. The other two headers have holes which do not have these thrust bearings. With this construction, it is possible to maintain a good setting of the distributor and good engagement of the pivots with the ledges or bearings under the opposing forces, and great care need not be employed in machining the same.

Another object has to do with drainage and with the prevention of leakage. By locating the reverse connections in the way proposed, it is possible to readily drain off the water. This may be of considerable importance, as where a plant, employing the heat exchanger, is used but a few hours a day and is then shut down and allowed to become cold. In the proposed construction, there is no head of water left in any of the units. Con-

2

sequently, there is nothing to freeze, as is the case with certain prior art structures where water is left in the passages and the plant is shut down during freezing weather. And due to the novel construction, there is practically no leakage.

Other objects have to do with efficiency coupled with ease of operation and economy, streamlining, cleanliness, saving in floor space and the like.

These various objects and advantages will be more fully understood upon reference to the following detailed description taken in connection with the accompanying drawings, and the scope of the invention will be particularly pointed out in the appended claims.

In said drawings,

Fig. 1 is a vertical sectional view of a heat exchanger constructed and arranged in accordance with the present invention, the plane of section being indicated by the line 1—1 of Fig. 3;

Fig. 2 is a top plan view, a portion being in section, indicated by the line 2—2 of Fig. 1;

Fig. 3 is a horizontal section taken a little lower down, indicated by the line 3—3 of Fig. 1;

Fig. 4 is a transverse section indicated by the line 4—4 of Fig. 2 and illustrating especially the fitting of the units into the grooves formed in the under side of the distributor;

Fig. 5 is a transverse vertical section taken on a plane indicated by the line 5—5 of Fig. 2;

Fig. 6 is a central vertical section through the second header from the top, indicating the separable hollow pivot on a large scale; and

Fig. 7 is a similar section of the lowermost header and its pivotal connection.

Throughout these figures, like characters refer to like parts.

The principal parts of the exchanger include a main frame A, a series of vertical heat exchange units B, appropriately positioned headers C¹, C², C³, interposed hollow hinge connections D¹, D², D³, a distributor E located above the units and resting upon the top of the same, and a receiver F located beneath the units.

The main frame A includes a base portion in which the receiver F is located, and an upright supporting portion which carries the headers. The base portion includes a bottom 10 which is provided with sides 11, 12, a forward end 13, and a transverse partition 14 extending between the side walls 11, 12. These parts form the boxlike construction of the receiver F. The bottom 10 of the receiver is depressed somewhat, toward the forward end of the receiver, as indicated at 15, and thus provides for draining the liquid from the receiver through an outlet pipe 16. The lat-

ter serves to carry off the liquid which is collected after being treated by the units B. The bottom 10 is provided with short legs 19. The latter engage the supporting surface on which the exchanger stands. The upper edge of the receiver is shaped so as to provide a reentrant angle 20 and an outwardly extending lip 21 just above it. This groove and lip cooperate with the hinged cover ordinarily employed to enclose the units. A cover, or covers, are not shown in the present drawings, but obviously may be like those of Patent No. 2,040,947. The material out of which the bottom 10 and associated receiver F are made is sheet metal, preferably of the stainless kind.

The vertical portions of the frame A preferably take the form of a rectangular frame comprising vertical channel members 22, 23, which are secured to the bottom 10 and walls 14 of the base at the back of the exchanger. These members 22, 23, are connected at their top by a channel 24. All of these parts are composed of metal, preferably of the stainless variety, and are secured together in any suitable way as by welding. A solid upright structure for the support of the four headers C¹, C², C³, is thus provided.

The heat exchange units B are substantially the same as those disclosed in the aforesaid Patent No. 2,040,947. In the present instance, each unit has an upper section 27 and a lower section 28. The units as a whole are made up of two sheets of metal, preferably stainless, which are pressed to form grooves or depressions such that when the two sheets are brought together and secured together by welding or otherwise, as desired, there will be passageways for the heat exchange medium through the interior of each section. The passages in the case of section 27 will extend from the inlet 29 to the outlet 30. Similarly, in the case of section 28, the passages will extend from the inlet 31 up to the outlet 32.

The four headers C¹, C², C³, are associated with four pivots or pivotal connections D¹, D², D³, as shown. The inlet 29 communicates with the pivotal connection D¹. The outlet connection 30 communicates with the connection D². The inlet connection 31 communicates with the lowermost connection D³, and the connection 32 communicates with the connection D⁴ next to the lowermost.

Without going further into the details of construction of the units B, it may be pointed out that the flow of the heat exchange medium in the case of the upper section 27 will extend from the inlet 29 through parallel paths to the space 33 at the right as viewed in Fig. 1, thence through parallel paths to the space 34 at the left, thence by similar paths to the space 35 at the right, thence to the space 36 at the left, and so on back and forth to the uppermost passages and thence out through the outlet 30. The flow of the heat exchange medium in the case of the lower section 28 will include passages which extend back and forth through the interior and finally emerge at the outlet connection 32. The units B also have their inner and outer ends turned laterally to form strengthening flanges 37, 38. Thus, there is a pair of inlet headers and a pair of outlet headers operatively connected with the heat exchange units. Drip rings 26 serve to confine the drip of the condensate in a well-known manner. In other words, it causes the drip to fall to the rear of the wall 14.

The headers are spaced as shown, and extend between the uprights 22 and 23 of the main

frame A. These headers differ amongst themselves but slightly, and accordingly the uppermost header C¹ may be described and later the differences in the others will be pointed out. This header comprises a hollow body 39 which is connected at its rear to an outlet pipe 40. The body 39 is secured near its ends by screws 41 and 42 to the uprights 22 and 23 of the frame A. The upper horizontal face of the header is thus connected to lie in a horizontal plane when in assembled position. The upper wall of the header body 39 is provided with a thickened portion 43 through which the openings for the pivots extend. This thickened portion 43 is of the same length as the header. Each opening extends at right angles to its upper face through the thickened portion 43 to the interior 44 of the header. These openings, designated 45, are of varying diameter, that is, in each opening there is an upper diameter a, an intermediate diameter b, and a lower diameter c. (See Fig. 5.) These are made as illustrated, a packing ledge or step 46 being provided between the large and intermediate diameters, and a thrust bearing or ledge 49 being provided between the intermediate and small diameters.

The vertical portion 51 of the elbow-shaped pivotal connection D¹ engages the thrust step 49 and packing 52, the packing step 46, which is slightly inclined downward toward the center of the bore as shown. Thus the overhanging ledge 50 provides a thrust bearing step for the pivot and the ledge 49 a packing step. A packing gland nut 53 surrounds the tube 51 and is threaded at 54 into the mouth of the opening. By screwing down the packing nut 53, pressure is brought to bear upon the packing rings and they form a tight connection with the tubular portion 51 of the pivot. Thus, the end of the vertical portion 51 of the pivot engages the step bearing 50, and the packing engages the packing bearing 46; when the parts are in position, the nut 53 serving to force the packing down tight. It will be noted that there is a small clearance 57 between the nut 53 and the tubular portion 51. Likewise, there is a similar clearance 58 contiguous to the thrust bearing 50. The former provides for easy manipulation of the nut 53 and a tight binding of the packing rings 52 upon the pivot portion 51. Likewise the latter provides for a guiding action of the end of the pivot into its seat upon the thrust bearing 50. This description relates, as we have before pointed out, to the first or uppermost header C¹.

The header C² is the same in construction as the header C¹, but is reversely positioned upon the frame A. This reverse positioning causes an opposition in the forces applied to the units by the contained medium, and thus reduces the resultant force along the axis of rotation. Where a readily vaporizable heat control medium, such as ammonia, is employed, this pressure may be considerable. The header C² communicates with a supply pipe 46.

When we come to the header C³, we find it is practically the same as headers C¹ and C² except that the opening is not provided with the overhanging ledge 50, but is cut away as shown at 59. Thus the interior diameter of this portion of the header is larger than the diameters of corresponding portions of the headers C¹ and C². In other words, the bore of the opening in this case has but two diameters, that of the large diameter a and that of the intermediate 75 diameter b. By continuing the cutting of the

drill on down through the material of the thickened portion 43 of the header body 39 until it enters the interior 44, this may be accomplished. All this is clearly illustrated in Fig. 7. With such construction it is obvious that the lower ends of the vertical portion of the pivotal connection D³ need not be cut off evenly or, if so cut, need not be of the same length as the corresponding parts 50 of connections D¹ and D². This is indicated in Figs. 1 and 7 by the vertical portions 55 which are made longer than the portions 51 of connections D¹ and D².

Instead of having the portions 51 and 55 of different lengths as recited, they may still be of the same length. Thus, various combinations may be used. It is only essential that two of the connections, one the reversed connection, should have the vertical portions the same as the portion 51 of connection D¹. The others may be the same or otherwise as indicated.

The inlet header D³ (the lowermost header) is connected to a supply pipe 48 and the outlet header D³ (the one above the lowermost) is connected to an outlet pipe 47.

It will be apparent that by making the upper faces of the headers C¹ and C³ and the lower face of the header C² perfectly horizontal, and bringing the ends of the tubular portions 51 or 55, as the case may be, to an exact position with reference to the upper edge of the particular unit under consideration, the parts when assembled may be brought to bear perfectly against the thrust bearings 50 and then any slight variation in the position of the headers C¹ and C² will be taken up by the tolerance allowed in connection with the screws 41, 42, which secure these headers in place.

It will be noted that it will not require the same accuracy of adjustment with reference to the other headers, namely, the header C³, C², since the long portion 55, which enters into these headers, can pass down through the enlarged opening, indicated at 59, or if short, can be guided sufficiently by the guiding walls of the intermediate diameter opening the same as in the case of the headers C¹ or C², having the thrust bearing 50.

Referring to the pivotal connection D¹, it will be noted that besides the vertical portion 51, it comprises also a horizontal portion 60 which is secured to the adjacent portion of the unit B at the point 30. Thus, by the entire connection, the interior of the unit B is connected through the pipe portions of the pivot 60 and 51, and the hollow interior of the header to the pipe 40. The same is true of the pipe connections D³ which also comprise a horizontal portion 61, in one case connected at 32 to the unit, and in the other case at 31.

In the case of the reverse connection, D² is the pivotal element and comprises the vertical portion 51, previously referred to, and a short horizontal portion 62 which terminates in an inclined head 63. This is shown on a large scale in Fig. 6. Cooperating with this is a nut 64 having a projecting ring 65 adapted to engage the head 63. The head 63 and ring 65 have mating inclined faces which engage each other. The nut 64 is interiorly threaded for engagement with the threaded exterior of the head 66. By screwing up the nut 64 upon the head 66, the connection is completed. By unscrewing the same, the connection is broken. Thus a quickly releasable coupling is provided.

Between the head 66 and the end of the hori-

zontal portion 62, is a gasket 67. This gasket is composed of fiber or other suitable material. It is the only point in the various connections of the header which employs a gasket.

Thus, from what has been said, it will be seen that each of the pivotal connections D¹, D², D³, constitutes an elbow-shaped communicating pivot extending outwardly from the units B and vertically into the openings 45 and two at least into thrust engagement with the thrust bearings 50.

Assuming that the parts are assembled as illustrated, if it then be desired to take down a unit, all that is necessary is to release or loosen the various packing nuts 53 and remove the coupling nut 64 from the head 66 of the horizontal projection 68 extending from the unit B. Then with the coupling nut 64 removed from the head 66, it is easy to swing the pivotal member, comprising the vertical portion 51 and the horizontal portion 62, to one side, out of the way, and then, by raising up upon the unit B, the entire unit is removed. When the same or a new unit is to be replaced, the operation is reversed. It will be noted that in so doing, the vertical portions of the elbow hinges may be easily slipped into the openings 45 in the headers C¹ and C³; and then when the vertical portion 51 of the uppermost header D¹ engages the thrust ledge 50, the pivotal portion of the connection D² may be swung back into place and the coupling nut 64 properly positioned. Then the various packing nuts 53 are screwed up so as to insure a proper connection.

When the connection D² is opened up, the upper section 21 is readily drained. Any water within it readily flows out through the inlet 29-68. Thus nothing is left within the heat exchanger to freeze, in case of cold weather.

The heat exchanger is ordinarily provided with a distributor E for supplying liquid to the several units. This may take the form of the distributor disclosed in the aforesaid Patent 2,049,947. The distributor bottom 71 is provided with suitable apertures 72 (see Fig. 4) which have vertical grooves 73 which fit over the upper edges of the units B. If a heat exchanger of a given capacity is supplied, it may be advisable to fit up only a fraction of the ultimate number of units of which the exchanger is capable. This may be done, in some jurisdictions, by filling up the apertures 72 of one or more of the rows with solder. When a new unit is to be put into service, the solder may be removed by melting it out. Similarly, the extra connections in the headers may be provided and plugged up by plugs.

Thus, in the case illustrated, there are three units and provision for a fourth. The fourth set of openings 45 are closed by plugs and washers, as indicated in the case of the header C¹ by a plug 74 and a washer 75. And the fourth row of holes 72 in the bottom 71 of the distributor E is closed by solder 76.

The distributor E need not be further described. Suffice it to say that it has a pipe connection 77 which enables liquid to be supplied to it.

Although but four headers are shown, it will be obvious that more might be employed and all the additional ones provided should have the arrangement preferably of the header C³, although from what has been said it will be clear that different arrangements might be employed.

Likewise still other modifications may be made in matter disclosed without departing from the

spirit and scope of the invention. Because of this fact, it is aimed, by the terms of the appended claims, to include all of these alterations and modifications which rightly come within the scope of the invention.

I claim:

1. A heat exchanger comprising an upright supporting frame, a heat exchange unit having an upper and a lower section, each section having an inlet at its bottom and an outlet at its top, a pair of inlet headers associated with said inlets, the upper section inlet being on a level with a low point in the passage of said section, a pair of outlet headers, all of said headers associated with said outlets being secured to said frame in vertical alignment and spaced relation, three of said headers having a horizontal upper wall and one of said headers having a horizontal lower wall, the latter of said headers being associated with the inlet of said upper section, each of said walls being provided with a vertical opening therethrough, each said opening having a packing step, the opening in said lower wall and one opening in one of said upper walls also having a thrust bearing step, four elbow-shaped communicating pivots extending outward from said unit and vertically into the openings in said headers, two into thrust engagement with said thrust bearings in said two headers, packing material resting upon said packing steps and surrounding the adjacent portions of the pivots respectively, a packing gland fitting against each said adjacent portion of the pivot and threaded into the header to compress the packing, and a quickly releasable coupling upon the reversely connected elbow-shaped pivot, whereby upon separating said coupling the upper section may be efficiently drained and the unit readily lifted from the headers.

2. A heat exchanger comprising a supporting frame, a heat exchange unit having two sections, an upper and a lower section, each having an inlet at its bottom and an outlet at its top, inlet and outlet headers associated with said inlets and outlets respectively, the headers associated with the inlet and outlet of said lower section and

5 with the outlet of said upper section having a horizontal upper wall and the header associated with the inlet of said upper section having a horizontal lower wall, each of said walls being provided with a vertical opening, each said opening having a packing step, the openings of the upper section headers being also provided with a thrust bearing step, four elbow-shaped communicating pivots each having a horizontal portion connected to said unit and a vertical portion connected to a header, the connection with the inlet of said upper section being from a low point in the passages of said section, the vertical portions of all of the pivots entering the openings in said headers and those entering the openings of the headers associated with said upper section passing into engagement with the thrust bearings thereof, packing material resting upon said packing steps and surrounding the adjacent portions of the pivots respectively, a packing gland fitting against each said adjacent portion of the pivot and threaded into the header to compress the packing, and a quickly releasable coupling upon the horizontal portion of the elbow-shaped pivot associated with the inlet of the upper section 10 whereby upon separating said coupling the entire upper section may be efficiently drained and the unit may be readily removed by lifting the unit when desirable.

30 WILLIAM RADTKE.
